US0D1044784S

(12) **United States Design Patent** (10) **Patent No.:** **US D1,044,784 S**
(45) **Date of Patent:** **** Oct. 1, 2024**

(54) **AUTOMOTIVE MILLIMETER-WAVE RADAR DEVICE**

(71) Applicant: **ARCADYAN TECHNOLOGY CORPORATION**, Hsinchu (TW)

(72) Inventors: **Kuan-Lin Huang**, Hsinchu (TW); **Shin-Lung Kuo**, Hsinchu (TW)

(73) Assignee: **ARCADYAN TECHNOLOGY CORPORATION**, Hsinchu (TW)

(**) Term: **15 Years**

(21) Appl. No.: **29/887,737**

(22) Filed: **Mar. 24, 2023**

(51) **LOC (14) Cl.** **14-03**

(52) **U.S. Cl.**

(57) **CLAIM**

The ornamental design for an automotive millimeter-wave radar device, as shown and described.

DESCRIPTION

FIG. 1 is a perspective view of an automotive millimeter-wave radar device showing our new design;

FIG. 2 is a front elevational view thereof;

FIG. 3 is a rear elevational view thereof;

FIG. 4 is a left elevational view thereof;

FIG. 5 is a right elevational view thereof;

FIG. 6 is a top view thereof;

FIG. 7 is a bottom view thereof; and,

FIG. 8 is a perspective view of the automotive millimeter-wave radar device viewed from another direction.

1 Claim, 8 Drawing Sheets
